4 Claims. (Cl. 123—65)

This invention relates to a method of scavenging high speed two-stroke internal combustion engines, more particularly those operating with a crank casing pump.

Port-controlled two-stroke internal combustion engines are already known, in which the scavenging ports lying opposite the exhaust ports are placed at an inclination towards the cylinder cover, for directing the scavenging medium along that part of the cylinder wall which is remote from the exhaust ports towards the cylinder cover and, driving the exhaust gases in front of them, to force them out of the cylinder. This flow along the cylinder walls causes a rotating mass to be trapped over the cylinder end, which consists of waste gases and cannot be swept out. When the equilibrium of this rotating mass is disturbed by the motion of the piston, the flow will adopt another, entirely uncontrolled course which completely upsets successful scavenging. Such machines depend entirely on the peculiar shape of the scavenging ports, the upper and lower bounding surfaces of the scavenging ports each having a curved form which is a continuous inward curvature in the same direction with respect to the cylinder wall and the radius of curvature of which continuously increases after entry into the cylinder. With such an arrangement it is possible only in the case of slow speed two-stroke engines to obtain stable conditions of flow. In high speed two-stroke engines this expedient fails, as in this case there can no longer be any stable conditions of flow in the cylinder.

In contradistinction thereto the novel feature of the invention consists in this, that the scavenging agent is introduced into the cylinder with such pressure and such velocity that it leaves the scavenging members in the form of free jets which draw the scavenging medium which has been released by the disintegration of the jet to themselves and hold it together in the cylinder. In this way the scavenging agent can be injected into the cylinder in the short period of time available in such a manner that it will remain in the same. The waste gases are no longer forced out of the cylinder but are only diluted by the scavenging agent. The scavenging jets entering the cylinder spread according to definite laws, somewhat in the shape of a pine-cone, sucking back the scavenging agent which has been released and become mixed with waste gases and keeping it in an ordered circulation in the cylinder. If this circulation be obstructed by a cylinder wall on that side of the scavenging jet

which is remote from the exhaust port and be assisted on the side facing the exhaust port by a depression in the piston, the scavenging jet can be completely deflected towards that side of the cylinder which is remote from the exhaust port. Through the deflection of the scavenging jets a rotating mass is produced in the cylinder, the equilibrium of which is no longer disturbed by the motion of the piston and in which the waste gas can be diluted in accordance with the quantity of scavenging agent injected. In high speed two-stroke engines, in which the flow takes place intermittently, good scavenging is in this way assured, independently of the arrangement and shape of the scavenging members.

The arrangement according to the invention is illustrated as applied to mixture compressing, port-controlled two-stroke internal combustion engines in the accompanying drawings, in which

Fig. 1 shows a longitudinal section through the cylinder with unilateral scavenging,

Fig. 2 a longitudinal section through the cylinder in another constructional form,

Fig. 3 a section on line III—III of Fig. 2,

Fig. 4 a longitudinal section through a cylinder in another constructional form,

Fig. 5 a section on line V—V of Fig. 4 and

Fig. 6 a longitudinal section through the cylinder with bilateral scavenging.

In the constructional form shown in Fig. 1 the exhaust port 2 and the scavenging port 4 are opposite one another at the inner cylinder end. The exhaust port 2 of rectangular cross-section is cast in the cylinder wall 3 and the scavenging port 4 of round cross-section is bored out of the cylinder wall 5. The scavenging port 4 has the form of a pressure nozzle with a rounded entering edge 8, which is in communication with a relatively wide supply passage 7 for the scavenging agent. The nozzle axis D is inclined at an angle β to the cylinder head 6. The supply passage for the scavenging agent is in communication with the crank casing (not shown) through a communicating port which is controlled by the piston 12.

As it descends, the piston 12 opens first the exhaust port 2 of the vertical height ca , whereby the exhaust gases are expanded. The piston 12 then opens the scavenging port 4 of the vertical height ce , so that the scavenging agent flows out of the supply passage 7 into the cylinder. In the scavenging port 4 having the form of a pressure nozzle the pressure drop of the scavenging agent is completely converted into velocity, so that the scavenging agent leaves the port as a

free jet 9 and spreads in the cylinder space somewhat in the form of a pine-cone. Through the suction action of the jet 9 at the nozzle opening the spread scavenging agent 10 which 5 mixes with the waste gases is carried back to the scavenging port 4, so that an ordered circulation of the gas about the jet axis D results, which keeps the scavenging agent 10 together in the cylinder and in this way prevents it leaving 10 prematurely through the exhaust ports 2. Only as the quantity of scavenging agent increases and as the dilution of the waste gases in the cylinder increases will gas 11 leave through the exhaust port 2. Thus, in contradistinction to 15 the so-called short-circuiting bow, a return motion 11a of the gas will be created above the piston 12 towards the nozzle opening as the place of greatest vacuum in the cylinder.

In the constructional example shown in Figs. 20 2 and 3 the scavenging port 4 has the form of a pressure nozzle of rectangular cross-section, which is directed towards the cylinder head 6 and the upper edge of which merges with a curve 13 into the cylinder wall 5. The curvature 13 25 is formed in the manner of an aero-foil profile 14. The upper edge of the scavenging port 4 is formed by an insertion piece 15 of the cylinder wall 5, which is fixed by screw bolts 16 to the cylinder. The piston 12 has a depression which increases in depth towards the side 17 of the scavenging port 4. On the piston 12 descending, the scavenging port 4 will first open to the extent αe , allowing burnt gas partially to 30 expand in the supply passage 1. Thereupon the 35 exhaust port 2 opens with the vertical height αa , allowing the cylinder to discharge. Only after the completion of the exhaust the communicating port (not shown) at the bottom end of the supply passage 1 opens, so that the scavenging 40 agent can emerge in the form of a jet through the scavenging port 4 which at this moment will already have opened sufficiently far. As the admission of the gases 11 to the scavenging jet 9 is 45 obstructed at the side remote from the exhaust port 2 by the screening action of the cylinder wall 5 and is assisted on the side facing the exhaust port 2 by the suction action of the piston depression 17, the scavenging jet 9 will be deflected through a certain angle γ . Owing to the 50 curvature 13, the deflection of the scavenging jet 9 takes place so gradually that the scavenging jet 9 will adhere to the cylinder wall 5. The scavenging agent 10 which becomes liberated by the disintegration of the jet and mixed with the 55 residual gases is thus only drawn back against one side of the scavenging jet 9, causing it to force the scavenging jet 9 against the cylinder wall 5. The gases 11 leaving through the exhaust port 2 are thus only relatively slightly 60 diluted by the scavenging agent.

In the example shown in Figs. 4 and 5 better scavenging conditions are obtained through the scavenging port 4 being rounded out not only at the upper and lower edge at 8, 13, but also at 65 the lateral edges at 18. The scavenging port 4 and the exhaust port 2 are each provided with a central bridging piece for the better guiding of the piston rings. The scavenging agent thus enters the cylinder in the form of two jets 9 70 which are also deflected laterally against the cylinder wall 5, so that the jet takes the form of a relatively thin layer 9a, along which the scavenging medium 10 which has been liberated through the disintegration of the jet is carried, 75 both in the longitudinal plane (Fig. 4) and in

the transverse plane (Fig. 5). In this case the piston depression 17 is made central.

In the constructional example shown in Fig. 6 the method is applied for bilateral scavenging. Two exhaust ports 2, 2' and two scavenging ports 4, 4' are in this case disposed respectively cross-wise at the inner cylinder end. In this case the flow 10 of the scavenging agent is symmetrical with respect to a longitudinal plane of the cylinder, which is determined by the exhaust ports 2, 2'. As in this case smaller nozzle cross-sections will suffice, both a more favourable heat stressing of the cylinder and better scavenging will result.

The nearer the pressure drop of the scavenging agent between the supply passage 1 and the cylinder approaches the critical pressure drop, the more compact will the scavenging jet be, where it emerges, and the better will consequently be the effect of the scavenging. An increase of the pressure drop above the critical drop must however be avoided, as in this case the jet would emerge at a greater pressure than the cylinder pressure and would therefore not retain its form in the cylinder. When the pressure drop approaches the critical drop, the velocity of the jet will approach the velocity of sound, which is the correct one for the state of the scavenging agent. The quantity of jet introduced per time unit is calculated not from the smallest nozzle cross-section αd , but in view of the constriction of the jet from the smallest jet cross-section αs . The angle of deflection γ of the scavenging jet depends in the first place on the angle of inclination β of the scavenging port 36 4 with respect to the cylinder axis. With a complete deflection of the scavenging jet 9 against the cylinder wall 5 (Figs. 2 and 4) the angle of deflection γ together with the jet angle α form the angle of inclination β .

The method may be applied to all forms of jet, irrespective of whether transverse, reverse or quick flow of scavenging is employed and irrespective of whether arrangements with a single port or several ports are provided. The method 4 is particularly suitable for high speed two-stroke engines having crank casing pumps, as in such engines, owing to the relatively high scavenging pressure, great scavenging velocities occur, which favour the forming and deflection of the scavenging jets.

What I claim is:

1. A method of charging a high-speed two-stroke internal combustion engine having a cylinder, an exhaust port, an inlet nozzle and a piston controlling fluid passage through the port and nozzle consisting in passing a charge through the nozzle at such pressure and velocity as to cause the charge to enter the cylinder as a free jet and thereby exert a suction effect upon the part of the charge released by the dispersion of the jet to produce an eddy tending to collect and hold the charge in the cylinder.

2. In a two-stroke internal combustion engine the combination of a cylinder, an exhaust port, an inlet nozzle and a piston controlling fluid passage through the port and nozzle, said nozzle being adapted to direct a charge into the cylinder at such pressure and velocity as to cause said charge to enter the cylinder as a free jet and thereby exert a suction effect upon the part of the charge released by the dispersion of the jet to produce an eddy tending to hold the charge in the cylinder, with said piston being hollowed in the portion thereof facing said nozzle.

3. A two-stroke internal combustion engine including a cylinder, an exhaust port, an inlet nozzle and a piston controlling fluid passage through the port and nozzle, said nozzle being adapted to direct a charge into the cylinder at such pressure and velocity as to cause said charge to enter the cylinder as a free jet and thereby exert a suction effect upon the part of the charge released by the dispersion of the jet to produce an eddy tending to hold the charge in the cylinder, the wall of the cylinder adjoining said nozzle being rounded to merge with said nozzle, said nozzle having an aerofoil profile.
4. A two-stroke internal combustion engine including a cylinder, an exhaust port, an inlet nozzle and a piston controlling fluid passage through the port and nozzle, said nozzle being adapted to direct a charge into the cylinder at such pressure and velocity as to cause said charge to enter the cylinder as a free jet and thereby exert a suction effect upon the part of the charge released by the dispersion of the jet to produce an eddy tending to hold the charge in the cylinder, a member inserted in the cylinder wall and presenting a rounded surface joining the nozzle and cylinder wall.

WALTER BOXAN.
